Letters Patent No. 3017 Dated Decr. 26-1863

Design for a Trade-Mark.

The schedule referred to in these letters Patent and making part of the same.

To all whom it may concern:

Be it known that I, Israel A. Powell of Lawrenceville, in the County of Lawrence and State of Illinois, have invented or produced a new and original design or paper as a Trade-Mark, and I do hereby declare that the following is a full, clear and exact description of the same:

The design represents an engraved label (for a bottle) at the top of which is the words, viz: Great American Remedy Dr. Powell's Liniment. Beneath this and about the centre of the label is a figure representing the American Eagle seated on the American shield with his wings extended to the righthand are three American flags and upon the left side and just above and behind the right wing of the Eagle a portion of a fourth flag is visible. Beneath the Eagle is a cannon a small portion of the mouth of which only is visible. At the foot of the shield and lying with one end upon the cannon is a Battle axe and bundle of sticks, upon the foot of which is represented as resting upon the ground and inclining to the left of the figure passing across the right corner of the shield and passing under and behind the Eagle's neck or head and extending to and very nearly touching the top of his right wing and upon the top of which pole is a representation of the Liberty Pole. At the bottom of this figure is a scroll passing from left to right over the bundle of sticks and under the liberty pole upon or with

genuine without the signature of J. A. Powell & Co. A copy of the
design is herewith annexed.

What I claim as my invention and desire to secure
by Letter Patent of the United States is: The design in its
position, arrangement and surroundings and including
the letters and words as a part of said design.
